UNITED STATES PATENT OFFICE.

GREENWOOD BAILEY AND WILSON ROBERTSHAW, OF BRADFORD, ENGLAND,
ASSIGNORS OF ONE-THIRD TO HERBERT FOSTER ANDERTON, OF BRADFORD,
ENGLAND.

APPARATUS FOR TREATING WOOL AND OTHER FIBROUS SUBSTANCES.

Application filed July 1, 1919. Serial No. 308,028.

To all whom it may concern:

Be it known that we, GREENWOOD BAILEY and WILSON ROBERTSHAW, subjects of the King of Great Britain, and residents respectively of 38 Aireville Road, Frizinghall, Bradford, in the county of York, England, and 248 Wellesley Terrace, Lumb Lane, Bradford, aforesaid, have invented a certain new and useful Improvement in 10 Apparatus for Treating Wool and Other Fibrous Substances, of which the following description, together with the accompanying sheets of drawings, is a specification.

Our invention relates to machines for 15 preparing and treating wool and like fibrous substances of the type known as "preparers", "gill boxes" and the like. In this type of machine it is usual for the wool that is fed to the first machine in the series to be there- 20 by gilled, passed through and drawn out of said machine into the form of a sliver which sliver is usually wound around a broad belt or apron which encircles two driving rollers. When said sliver has been made to 25 coil upon said moving belt until the desired number of layers have been wound thereon the attendant severs or breaks the sliver in order to be enabled to detach and remove same from its apron or driving belt. After 30 its removal from said travelling belt it is transferred to the next machine which is of a similar kind and which in like manner again gills or treats the wool or like fibrous substances prior to delivering same on the 35 other side thereof. This operation or process is repeated until a machine is reached wherein the sliver is delivered into a receiving can or receptacle in well known manner. All the said operations being well known to 40 those having a knowledge of the treatment of wool.

Our invention relates to this type of machinery and consists in the application of devices whereby the wool or fibrous sub- 45 stances, as it or they is or are delivered by the delivery rollers after passing through each of said machines, is or are received by our said apparatus or devices, thereby to be transferred to the next machine in such 50 order and condition that the handling of same by the attendant is entirely avoided in the stages between the machines. Thus after the feeding of the wool or like fibrous

substances to the first machine by the attendant, its transference afterwards, from 55 one machine to another until it is finally subjected to the last machine of the whole series is completed, is automatically effected or carried out by our said devices.

In the accompanying sheets of drawings 60 which are illustrative of our invention.

Fig. 1 is a side elevation of sufficient of the framework and certain operating parts of two adjoining machines to show the application thereto of our improved appa- 65 ratus.

Fig. 2 is a sectional elevation of the parts shown by Fig. 1 but with certain of the moving parts in altered positions.

Fig. 3 is plan of the apparatus shown by 70 Figs. 1 and 2.

Fig. 4 is an elevation on an enlarged scale showing certain parts hereinafter described.

Fig. 5 is a similar view, showing the parts 75 in different position from those illustrated in Fig. 4.

Fig. 6 is a plan of parts shown in Fig. 5. The framework A is that of the leading machine while the framework B is that of 80 the succeeding machine, the former being what is known as a "preparer" and the latter a "gill box", while the apparatus which is situated between the two is of our invention.

To the framework of the two machines A B are fixed the bars f , f^1 , f^2 and f^3 which extend vertically so that they may be joined together at their upper ends by the cross bars f^4 , f^5 and f^6 , f^7 . On these bars are 90 fixed bearings or supports 15, 15^a upon which is mounted a shaft 16 extending from one side of the apparatus to the other. On the outer ends of this shaft 16 are mounted to oscillate the arms 17, 17^a which extend 95 vertically on each side of the machine so that at their lower extremities there may be mounted two rollers 12 and 14, which are supported in brackets 19, 19^a fixed to the lower ends of said arms 17, 17^a. These 100 arms 17, 17^a have oscillatory motion transmitted to them through the rods 20, 20^a connected thereto and to the cranks 22^a and 22^b, carried by the driving pulleys 23, 23^a which are mounted upon a cross shaft 23^d. 105 These pulleys 23, 23^a derive rotary motion

through the belts 24, 24^a which take over the pulleys 23^b, 23^c mounted upon the shaft of the upper roller 2 in the machine A.

The upper roller 2 and the lower roller 3 of the machine A are the ordinary and well known delivery rollers in said machine A and these revolve in the directions indicated by the arrows *a* (Figs. 1 and 2). Around the lower roller 3 takes the ordinary delivery apron or belt 4. Upon appropriate supports 7 adjoining the rollers 2 and 3 in the machine A, we mount two rollers 5 and 6 which extend from side to side of the machine in front of the rollers 2 and 3.

Upon the bearings 15, 15^a fixed on the upper end of the framework *f*—*f*⁷ we mount three rollers 10, 11 and 13 which are free to revolve thereon and these are rotated by the driving aprons or belts 8 and 9. The belt 8 (which is endless) takes around the lower roller 5 and extends over the roller 10 down and around the lower surface of the roller 12 returning back over the upper surface of the roller 11. The belt 9 (which is also endless) takes around the upper roller 6 and extends over the upper surface of the roller 13 down under the roller 14 forward and over the top of the roller 11. Thus the adjoining portions *b* and *c* of the belts 8 and 9 are in close contiguity with each other at the two parts shown by Fig. 2. That is to say the two portions *b*, *c* thereof which extend from the rollers 5 and 6 to the roller 11 and from said roller 11 to the rollers 12 and 14 are relatively close together.

On the outer ends of the rollers 5 and 6 are fixed the toothed gearing wheels 5^a and 6^a respectively and these derive rotary motion from a wheel 3^a which is fixed on the end of the shaft of the roller 3 and gears with the toother wheel 3^b which also gears with the wheel 5^a.

The pendant arms 17, 17^a are counterbalanced by the weights 17^b and 17^c which are fixed upon arms extending horizontally from said arms 17, 17^a respectively.

Upon the arms 17, 17^a, is mounted a cross shaft 29, in appropriate bearings fixed upon said arms 17, 17^a. On this cross shaft 29 are fixed the pendant arms 28, 28^a which have horizontal arms 30 and 30^a. Connected to these arms 30, 30^a are connecting rods 31, 31^a respectively which reach to be connected to the levers 32, 32^a mounted upon the cross shaft 33. This shaft 33 is free to oscillate in bearings 33^b and 33^c mounted on the arms 17 and 17^a respectively, and is actuated as hereinafter described. Upon the lower ends 60 of the arms 28, 28^a is fixed the cross shaft 27. The position of the shaft 29 and the length of the arms 28, 28^a are such as to enable the cross bar 27 to pass beneath the rollers 12 and 14 when oscillated about said shaft 29 as hereinafter described. The

lever arms 32, 32^a are in such positions relatively to the cross shaft 33 that at one time as when in the position shown by Fig. 1 said arms 32, 32^a will raise against stop pieces *k* which are carried by the brackets 70 supporting said shaft 33 and when in this position said levers 32, 32^a will have moved the rods 31, 31^a and levers 30 and 30^a to cause the shaft 29 to oscillate and carry with it the arms 28 and 28^a in order to bring the cross bar or shaft 27 to the position to the left of the rollers 12 and 14 as shown by Fig. 1.

When the arms 17, 17^a are brought from their position shown in full lines Fig. 1 and in broken lines Fig. 2, into the position shown by full lines in said Fig. 2 in which position the cranks 22^a and 22^b will have reached their extremities shown by said Fig. 2 the levers 32^a and 32^b will have come in contact with a stop piece 34^a fixed upon the framework *f*⁴, *f*⁵ so as to cause said levers by the advancing movement of the arms 17, 17^a to move the rods 31, 31^a and other parts connected thereto to bring the bar 27 to the right of the rollers 12 and 14 as shown in full lines Fig. 2.

Mounted upon supports 50 are rollers 51 and 52 around which passes a travelling apron or belt 25 which travels between the two side plates 26, 26^a so that any fibrous substances placed thereon are fed to the machine B by said travelling apron 25.

The operations of the several parts are as follows: On the machine A delivering 100 or discharging the treated wool or fibrous substances from it, said wool or fibrous substances is or are received between the rollers 5 and 6 and between the travelling belts 8 and 9. The said travelling belts 8 and 9 receive said delivered wool between their two contiguous surfaces *b*, *c* and carry it upwards to and over the top of the roller 11 and beneath the roller 13 down to the rollers 12 and 14, which rollers 12 and 14 pay out or deliver said wool or fibrous substances on to the travelling belt 25 beneath.

As the travelling belts 8 and 9 are thus delivering the wool which has been supplied to them, the cranks 22^a and 22^b will be causing the arms 17, 17^a to oscillate so that the rollers 12 and 14 are carried from right to left and left to right over the travelling belt 25 thus depositing the wool which they transport in layers upon said travelling belt 25. In an ordinary manner these layers and fibres would be bent or folded upon each other at each end and in such folded condition would be presented to the next or succeeding machine, but this condition is undesirable so that to avoid such folding at the extreme ends of the movement of the rollers 12 and 14 in the path in which they oscillate, the bar 27 moves quickly beneath said rollers and thus breaks or severs the 130

sliver or sheet of fibres at each extremity of the path of movement of the rollers 12, 14, so that each layer of material deposited on the belt 25 is entirely separate from its preceding and succeeding layer. Hence the fibres are presented in the right direction and condition for being fed to the succeeding machine.

We may here observe that the apparatus we have herein described is (as is hereinbefore stated) mounted between pairs of machines in the place heretofore occupied by the attendant in order to transfer the fibres from one part to another so that whatever the number of machines may be in the series of machines used our said apparatus is mounted between each two of said machines in the series until the last machine is reached as will be understood.

Such being the nature and object of our said invention, what we claim is:—

1. A conveyor for carrying wool from one machine to another, comprising travelling belts or aprons, rollers situated near the delivery rollers of one of the preparing or gilling machines, bearings for said rollers, guiding rollers for said travelling belts, supports for said guiding rollers, oscillatory arms, bearings for said arms, means for imparting oscillatory motion to said arms, supplementary arms pivoted upon the oscillatory arms, a cross bar carried by the lower ends of said supplementary arms and means whereby additional or in-

dependent oscillatory motion is transmitted to said supplementary arms.

2. A conveyor for carrying wool from one machine to another, comprising travelling belts or aprons, rollers situated near the delivery rollers of one of the preparing or gilling machines, bearings for said rollers, guiding rollers for said travelling belts, supports for said guiding rollers, oscillatory arms, bearings for said arms, means for imparting oscillatory motion to said arms, supplementary arms mounted upon the oscillatory arms, a cross bar carried by the supplementary arms, connecting levers, said levers and means for operating same.

3. A conveyor for carrying wool from one machine to another, comprising travelling belts or aprons, rollers situated near the delivery rollers of one of the preparing or gilling machines, bearings for said rollers, guiding rollers for said travelling belts, supports for said guiding rollers, oscillatory arms, bearings for said arms, means for imparting oscillatory motion to said arms, supplementary arms, a cross bar carried by said arms, rods and levers for operating said arms, and devices fixed upon supports for operating said supplementary arms when the oscillating arms are approaching the extremity of their path of motion.

GREENWOOD BAILEY.
WILSON ROBERTSHAW.
